UNITED STATES PATENT OFFICE.

SAMUEL J. TODD, OF HIGHLAND PARK, MICHIGAN, ASSIGNOR OF THREE-FOURTHS
TO BEN C. HUGHES, OF DETROIT, MICHIGAN.

SPARK-PLUG.

1,168,921.

Specification of Letters Patent. Patented Jan. 18, 1916.

Application filed December 17, 1914. Serial No. 877,733.

To all whom it may concern:

Be it known that I, SAMUEL J. TODD, a citizen of the United States of America, residing at Highland Park, in the county of Wayne and State of Michigan, have invented certain new and useful Improvements in Spark-Plugs, of which the following is a specification, reference being had therein to the accompanying drawings.

- 10 This invention relates to improvements in priming devices for explosive engines, and more particularly to that type of priming device disclosed in my pending application filed Nov. 30, 1914, Serial No. 874,649. Besides having the same objects in view as disclosed in this pending application, the present invention aims to provide a novel insulator or porcelain body for spark plugs that will form a reservoir in the body of plug 20 for gasoline or a priming fluid, which is transferred, in measured or predetermined quantities, to the electrodes of the spark plug.

My invention will be hereinafter specifically described and then claimed, and reference will now be had to the drawing, wherein there is illustrated a vertical sectional view of a combined spark plug and priming device in accordance with my invention.

- 30 The reference numeral 1 denotes a spark plug body made of metal with the lower end thereof reduced and exteriorly screw-threaded, as at 2, whereby the spark plug body can be mounted in or connected to the wall 3 of a multi-cylinder explosive engine. The spark plug body 1 has a longitudinal cylindrical bore 4 and the upper end of said bore is enlarged to provide an annular shoulder 5 and a cylindrical chamber 6.

- 40 7 denotes an insulator or porcelain body of less diameter than the chamber 6, said body having collars or peripheral flanges 8 and 9 engaging the walls of the chamber 6 and positioning the body 7 concentrically 45 of said chamber. The lower end of the body 7 extends into the bore 4 and the lower side of the collar 9 is beveled, as at 10 to rest upon a washer 41 seated upon the annular shoulder 5. The upper end 11 of the porcelain body 7 extends above the spark body 1 and is surrounded by a nut 12 screwed in the upper end of the spark plug body 1, said nut engaging a washer 13 upon the upper side of the collar 8.

- 55 14 denotes a longitudinally disposed valve

body carried by the spark plug body 1, said valve body having tapering longitudinal bore 15 for a valve plug 16. The plug 16 is rotatable in the bore 15 and is retained therein by a nut 17 or other fastening means 60 at the lower end of the valve plug. The upper end of the valve plug is reduced and machined to provide a small pinion 18 that meshes with a large pinion 19 rotatable upon the nut 12. The large pinion 19 has a 65 radially disposed crank 20 to facilitate rotating the pinions whereby movement is imparted to the valve plug 16. The crank 20 can be operated through the medium of a lever 21 common to a plurality of the devices, and the elements 18 to 21 inclusive simply constitute a conventional means of imparting movement to the valve plugs of the devices.

The valve plug 16 has a chamber 22 adapted to hold a predetermined quantity of gasoline or other fuel. The plug 16 has a port 23 at the upper end of the chamber 22 and the port 23 is adapted to communicate with a port 24 in the valve body 14 establishing 80 communication between the bore 15 of the valve body 14 and the chamber 6 of the spark plug body 1.

The valve plug 16 intersects an angularly disposed port 25 that has the inner end 85 thereof in communication with the bore 4 of the spark plug body 1. The outer end of the port 25 is closed by a detachable plug 26, and the lower end of the valve plug 16 has a port 27 adapted to establish communication between the port 25 and the chamber 22. The port 27 is in an opposite wall of the chamber 22 to that of the port 23 whereby one of said ports will be always closed by a wall of the bore 15. In other words, the 95 valve plug 16 alternately establishes communication between the ports 23 and 24 and the ports 25 and 27.

The wall of the spark plug body 1, opposite the port 24, has a port 28 with the walls 100 thereof screwthreaded to receive a supply tube or pipe 29 adapted to be connected to a gasoline or fuel reservoir (not shown). Gasoline or fuel can be fed to the priming device by gravity, pressure feed, or in any 105 manner that will maintain a constant supply to the priming devices of a multiple cylinder explosive engine.

The porcelain body 7 and the collars 9 thereof coöperate with the walls of the 110

chamber 6 in forming an annular reservoir or compartment 30 for gasoline or fuel. With the valve plug 16 in the position shown in the drawing, the chamber 22 of 5 said valve plug receives gasoline or fuel from the reservoir 30 and by rotating the valve plug 16 a half revolution the port 27 registers with the port 25 and the measured quantity of gasoline is delivered to the bore 10 4 of the spark plug body 1. The lower end of the spark plug body 1 has an electrode 31 coöperating with an electrode 32 of the porcelain body 7 in producing a jump spark which ignites the gasoline or fuel admitted 15 to the bore 4, causing an explosion for starting purposes. As porcelain body 7 is capable of absorbing and holding heat, the gasoline or fuel in the reservoir 30 will be heated and placed in better condition for 20 ignition.

From the foregoing it will be observed that I have dispensed with the metallic reservoir around the porcelain disclosed in my pending application, also packing incident 25 to the use of the reservoir. In the present instance the collars 8 and 9 of the porcelain body 7 form an important function and the washers associated with said collars insure a non-leakable reservoir around the 30 porcelain body.

While in the drawing there is illustrated a preferred embodiment of my invention, it is to be understood that the structural elements are susceptible to such modifications 35 and variations as fall within the scope of the appended claims.

What I claim is:—

1. In a combined spark plug and priming device, a spark plug body, an electrode and a 40 body of insulation material in said spark plug body for said electrode and coöperating with said body in forming a reservoir adapted to receive fuel for priming purposes.

45 2. In a combined spark plug and priming device, a spark plug body, an electrode and an insulator for said electrode in said spark plug body coöperating with said body in forming an annular reservoir adapted to receive fuel to be heated by said insulator for priming purposes.

50 3. In a combined spark plug and priming device, a spark plug body, an electrode, a porcelain body in said spark plug body as 55 an insulator for said electrode and provid-

ing an annular fuel reservoir, and means carried by said spark plug body for transferring measured quantities of fuel from the reservoir to the inner end of said body.

4. The combination with a spark plug 60 body and an electrode, of an insulator therein for said electrode and providing an annular fuel reservoir, and means carried by said spark plug body controlling the outlet of fuel from the reservoir. 65

5. The combination with a spark plug body, and an electrode of a porcelain body therein as an insulator for said electrode, collars carried by said porcelain body and coöperating with said spark plug body in 70 providing a reservoir, and a valve in communication with the reservoir for controlling the outlet thereof.

6. The combination with a spark plug body and an electrode coöperating therewith in providing a spark gap of an insulator for said electrode in said spark plug body coöperating therewith in providing a reservoir, a ported valve body in communication with the reservoir and a chambered 80 valve plug in the valve body adapted to alternately register with the ports of said valve body.

7. The combination with a spark plug body and an electrode coöperating therewith in providing a spark gap of an insulator for said electrode in said spark plug body coöperating therewith in providing a reservoir, a ported valve body in communication with the reservoir, a chambered valve 90 plug in the valve body adapted to alternately register with the ports of said valve body, and means on the upper end of said spark plug body for imparting movement to said valve plug. 95

8. In a spark plug having an electrode providing a spark gap, a body of insulation material for said electrode, means for maintaining fuel in communication with said body of insulation, and means in communication with said fuel containing means adapted to deliver predetermined quantities of fuel to the inner end of the spark plug. 100

In testimony whereof I affix my signature in presence of two witnesses.

SAMUEL J. TODD.
